INKING RIBBON MECHANISM

Robert E. Paris, Poughkeepsie, John H. Bakelaar, Binghamton, and Emerson F. Comstock, Maine, N. Y., assignors to International Business Machines Corporation, New York, N. Y., a corporation of New York

Application January 14, 1948, Serial No. 2,206

9 Claims. (Cl. 242—55)

1

This invention relates to mechanism for feeding inking ribbons such as are used in various kinds of business machines; for example, typewriters, adding machines, and record controlled accounting and statistical machines.

The broad object of the present invention is to provide an improved ribbon feeding and reversing mechanism suitable for use in business machines.

An object is to provide a ribbon feeding and reversing mechanism which is completely power-operated and does not impose any additional load on the means for actuating the feeding mechanism during the period of reversal of the feed of the ribbon.

An object is to provide a ribbon feeding mechanism which is capable of effecting relatively large movements of the ribbon, which movements may be controlled very readily.

An object is to provide a ribbon feeding mechanism in which the feeding and reversal of the ribbon is completely electrically controlled.

An object is to provide a ribbon feeding mechanism which is capable of being applied to a large number of different types of business machines.

An object is to provide a ribbon feeding mechanism which may also be used for feeding carbon ribbons or hectograph ribbons.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view showing the ribbon mechanism attached to a record controlled accounting and statistical machine.

Fig. 2 is a left-hand side elevation of the mechanism shown in Fig. 1.

Fig. 3 is a large scale front view in elevation of the left-hand ribbon feeding unit.

Fig. 4 is a horizontal section on the line 4—4 of Fig. 3.

Fig. 5 is a plan view partly in section of the mechanism shown in Fig. 3.

Fig. 6 is a detail view on a large scale showing the end of the clutch shifting lever and shows the clutch in disengaged position.

Fig. 7 is a view similar to Fig. 6 but shows the clutch in engaged position.

Fig. 8 is a large scale front elevation of the right-hand ribbon unit.

Fig. 9 is a plan view partially in section of the mechanism shown in Fig. 8.

Fig. 10 is a vertical section on the line 10—10 in Fig. 9.

Fig. 11 is a wiring diagram.

Fig. 12 is a detail view showing the feed disk for the carbon ribbon in place on the right-hand ribbon feed unit.

2

In the drawings the mechanism is shown as applied to a perforated record card controlled accounting and statistical machine but it will be understood that the mechanism is not limited in application to the particular type of machine disclosed in the drawings, but may be readily applied to other record controlled machines and to other types of machines, such as typewriters and adding machines, merely by modifying the manner of pulsing the magnets and the manner in which the power is applied to the ribbon mechanism. This will be made clearer hereinafter.

The ribbon mechanism comprises a right-hand unit generally designated RHU and a left-hand unit LHU in Figs. 1 and 2. These units include the right-hand bracket 28 which supports the right-hand unit RHU and the bracket 24 which supports the left-hand unit LHU. These brackets are secured to parallel fixed main frame members 22 which, in the illustrated embodiment of the invention, also support the platen 23 around which the work sheet 24 is fed.

The printing mechanism is generally designated 25 in Figs. 1 and 2 and includes the type elements 26 which are operated in a suitable fashion to make impressions on the work sheet 24 through the inking ribbon in a manner which need not be discussed herein since the specific form of the printing mechanism is not important. The printing mechanism is supported on two parallel frame members 27 which are located between the frame members 22 and parallel therewith. The right-hand unit RHU is the simpler of the two units and for that reason will be discussed first with reference to Figs. 1, 2, 6 to 10. It will be understood that the left-hand ribbon feed unit is a mirror image of the right-hand unit and, with one exception, contains all of the parts of the right-hand unit.

Secured to the top of the bracket 28 is a plate 28 provided with a vertical bushing 28a (Figs. 8, 9, and 10) in which is journaled the right-hand ribbon spool drive shaft 29. This shaft is shouldered at its upper end to provide a reduced portion 29a on which is received the right-hand ribbon spool 30 and the extreme upper end of the shaft 29 is threaded to receive the knurled thumb screw 31 by means of which the spool 30 is retained on the shouldered portion 29a.

Secured to the shaft 29 adjacent the shouldered portion 29a is a collar 32 (Fig. 10) which is pinned to the shaft and has a pin 32a loosely received in a hole in the side of the ribbon spool 30 to key said spool to the shaft 29. The collar 32 is shouldered to act as a seat for the multipronged spring 33, the prongs of which press downwardly on a disk 34 loose on the shaft 29. Interposed between disk 34 and the plate 28 is a ring of friction material 35 which is centered with respect to the shaft 29 by means of a loose washer 36. The spring 33 presses the disk 34 downwardly which

in turn presses the washer 35 against the plate 28 and acts as a brake for the shaft 29 to prevent spinning of the ribbon spool 30 when the latter is unwinding.

Secured to the lower end of the shaft 29 is a toothed clutch disk 37 (Figs. 8 and 10). Coaxial with the shaft 29 is a vertical drive shaft 38 which is journaled in the bracket 20 and carries at its lower end a bevel gear 39 meshing with a bevel gear 40 secured to a short shaft 41 (Fig. 1) journaled in the right-hand frame plate 22. The upper end of the shaft 38 has secured to it a hub 42 formed with a flange 42a loosely supporting a clutch disk 43 which confronts the clutch disk 37. The clutch disk 43 is slidably keyed to the hub 42 by means of three pins 43a which are loosely received in holes in the clutch disk 43 but the clutch disk is free to be shifted axially upward to engage the clutch disk 37. Normally a multipronged spring 44 urges the clutch disk 43 downwardly and holds it in engagement with the top side of the flange 42a in which position the disks 37, 43 will be disengaged. The multipronged spring 44 is retained under tension on the hub 42 by means of a suitable wire retaining ring sprung into a groove formed in the hub 42a.

The clutch comprising the members 37, 43 is engaged by means of a solenoid designated RHF (Figs. 8 and 10) and hereinafter termed the right-hand feed magnet. This solenoid is mounted on the bracket 20 and has its plunger 45 pivotally connected to one arm of a clutch operating lever 46 pivoted on the pin 47 carried by the bracket 20. The left-hand end of the lever 46 has a stud 48 (see Figs. 6 and 7 also) on which is rotatably mounted a beveled disk 49. Normally, when the solenoid RHF is deenergized, the disk 49 is just clear of the clutch disk 43 but, upon energization of the solenoid RHF, the disk 49 is brought into engagement with the clutch disk 43 and the beveled portion of the disk 49 cams the clutch disk 43 upwardly into engagement with the clutch disk 37 as shown in Fig. 7, establishing a driving connection between the right-hand ribbon spool shaft 29 and the vertical drive shaft 38. It is quite apparent that the extent to which the ribbon spool 30 will be rotated will depend on the duration of the impulse to the magnet RHF. It is thus possible to obtain a long or short feed of the ribbon merely by controlling the duration of the pulse to the right-hand feed magnet RHF. The manner in which these pulses are imparted to the feed magnet RHF and the companion feed magnet for the left-hand unit, designated LHFM, will be made clear hereinafter.

From the spool 30, as clearly illustrated in Fig. 1, the ribbon R (shown in solid lines) is led from the right-hand ribbon spool 30 to the right across the face of a guide shoe 50 secured to the top surface of the plate 28, around a guide pulley 51, then forwardly, or downward in Fig. 1, around a second guide pulley 52. The ribbon is then carried across the machine between the work sheet on the platen 24 and the type elements 26 to the left-hand unit LHU which is similarly provided with guide rollers 51, 52. Pivotaly mounted on a stud 53 (Figs. 1, 8, and 9), carried by the right-hand plate 28, is a ribbon control lever 54 having two lugs 54a which will just clear the shoe 50 and the ribbon R when the lever 54 is in either of its two possible operated positions so that the ribbon may move freely between the lugs 54a and the shoe 50. At a few inches from the point where the ribbon R is anchored to the spool 30, there is secured an enlargement 55, such as a metal clip

or staple, of greater thickness than the clearance space between the lug 54a and the shoe 50 so that, as the ribbon becomes exhausted from the right-hand spool 30, the enlargement 55 will eventually engage the right-hand lug 54a in Figs. 1 and 9 and rock the control lever 54 in a clockwise direction, this movement being limited by a pin 56 carried by plate 28 and which extends through an arcuate slot in the ribbon control lever 54. The lever 54 is held in either of its alternate positions by a toggle spring 57 connected to the pin 56 and to a pin carried by the lever 54.

The ribbon control lever 54 is formed with a downwardly extending lug 54b (Figs. 8 and 9) which engages the operating arm 58 of a sensitive switch designated RHC and upon the right-hand contacts. This switch is of a conventional form known in the art in which a very small movement and a relatively light force operates contacts to open or close a circuit. The switch RHC may be of a form known under the trade names of "microswitch" and is of the normally closed circuit type which is opened whenever the lever 54 is moved to the left or clockwise in Fig. 9.

The movement of the lever 54 by the enlargement 55 brings the left-hand lug 54a into the position now occupied by the right-hand lug in Fig. 9 so that, when the spool 30 starts to wind the ribbon, the enlargement 55 will engage the left-hand lug 54a and rock the lever 54 back to the position of Fig. 9.

For a purpose which will be made clear hereinafter, there is pivoted on a stud 59 (Fig. 9) carried by the plate 28 an arm 60 on which is rotatably mounted a pressure roller 61. The arm 60 is held against a stop pin 62 by means of a spring 63.

The left-hand ribbon unit LHU includes all of the parts so far described with the exception of the arm 60, the pin 62, and the spring 63 and these parts are similarly designated in Figs. 1 to 5 inclusive, the only exception being that the magnet is designated LHFM signifying left-hand feed magnet.

The shafts 41 for the two feed units are located in axial alignment with each other and are provided with gears 64 (Figs. 1 and 2) which mesh with large gears 65 journaled on studs 66 carried by the arms 67. The latter are journaled on the shafts 41 and are urged in a counterclockwise direction (Fig. 2) by the springs 68, movement of the arms being limited by eccentric studs 69 carried by the plates 22. The gears 65 mesh with gears 70 on a cross shaft 71 journaled in the frame plates 27. A gear 72 carried by the shaft 71 meshes with a gear 73 which is part of a train of gearing driven by the main shaft 74 and which includes the gears 75, 76, 77 and the gear 78 on the main shaft 74. The shaft 74 is driven continually by a motor (not shown), consequently both of the vertical shafts 38 rotate at all times while the machine is in operation and it is apparent that the ribbon may be fed in either direction merely by selectively energizing the feed magnets RHF, LHFM to cause the ribbon to feed (Fig. 1) in the direction denoted by the prefix letters R, L of the feed magnets. Thus when the magnet RHF is energized the ribbon R will feed to the right in Fig. 1.

The operation of the ribbon mechanism will now be described with reference to Fig. 11 showing the manner in which the magnets LHFM, RHF may be selectively energized under control of the ribbon itself to cause the ribbon to

automatically reverse its direction of feed when either spool becomes exhausted. It should be remarked at this point that the sensitive switch RHC for the right-hand unit RHU is of the normally closed type which is opened whenever the switch operating arm 56 is rocked clockwise by the control lever 54 for the right-hand unit.

In Fig. 11 the letters CB refer to a circuit closing device of some sort which is operated at periodic and appropriate intervals during the cycle of operation of the business machine to cause the ribbon to feed. The number, and points at which the contacts CB operate will be determined by the type of machine and the relative timing of the printing operations. In a record controlled accounting and statistical machine it may be necessary that the contacts CB close during that part of the cycle in which printing operations are not being effected as movement of the ribbon during such operations may produce blurred impressions. These contacts CB may be driven from any suitable shaft or device in the machine which has the appropriate time of operation. In the event that the ribbon mechanism were applied to a typewriting machine, for example, the contacts CB could be operated by a universal bar actuated or controlled by the type bar to insure that the feeding of the ribbon will take place after the printing operation has been effective. If desired the shaft 71 may be driven by an independent motor or, if the invention were incorporated in a typewriting machine of the power operated type, the shaft 71 may be driven by suitable gearing to the main drive motor or power roller for the typewriting machine.

As soon as current is turned on the line wires W1, W2 there exists the possibility of a circuit through the contacts CB and the right-hand feed magnet RHFM through the contacts c of the relay R1 when the contacts CB close at the appropriate point in the machine operating cycle. It will be assumed that the switch RHC is closed and the switch LHC is open which is the normal condition when the ribbon is being fed in either direction. The impulsing of the magnet RHFM causes the clutch members 37, 43 for the left-hand unit to be periodically engaged, resulting in counterclockwise rotation of the right-hand ribbon spool 30, thereby causing the ribbon R to be fed to the right, the extent of which will be determined by the duration of the current pulse through the magnet RHFM and also by the amount of ribbon already piled on the spool. Naturally, as the radius of the ribbon accumulated on the spool increases, the ribbon will be fed to an increasingly greater extent until eventually the enlargement 55 on the left-hand spool 30 will engage the left-hand lug 54a (Fig. 1) and rock the left-hand control lever 54 counterclockwise, thereby causing the left-hand switch LHC to close. This causes the relay R1 to become energized by a circuit through the switches LHC, RHC, and opens the contacts c, thereby stopping the impulsing of the right-hand feed magnet RHFM and, by closing contacts b, causes the impulsing of the left-hand feed magnet LHFM. At the same time, the contacts a of the relay R1 close and establish a holding circuit for the relay R1 through the right-hand switch RHC. The pulsing of the left-hand feed magnet LHFM now continues, causing the ribbon to be fed to the left until eventually the enlargement 55 for the right-hand end of the ribbon engages the right-hand control lever 54 and rocks it clockwise (Fig. 1) to open the switch LHC. This will

5

cause the de-energization of relay R1 and contacts c will reclose to cause pulsing of the right-hand magnet RHFM to again take place and the ribbon will now feed to the right as before.

After each operation of a lever 54 the reversal of the feed of the ribbon will cause the enlargement 55 to engage the left-hand lug 54a in the case of the right-hand unit RHU, or the right-hand lug 54a in the case of the left-hand unit LHU, and restore the lever 54 to the condition shown in Fig. 1 which is the normal condition when the ribbon is feeding in either direction. Once the relay R1 is energized the re-opening of the switch LHC has no effect and, on the other hand, once the relay R1 becomes de-energized, the reclosing of the switch RHC has no effect.

In order to feed a carbon ribbon or a hectograph ribbon it is not necessary to use the reversing feature since hectograph and carbon ribbons are only used once and discarded.

For the purpose of feeding a carbon ribbon the right-hand ribbon spool 30 is removed and a knurled feed wheel 79 (Fig. 12) is substituted in place of the ribbon spool, the arm 66 being swung in a counterclockwise direction far enough to permit the insertion of the feed wheel 79. The latter is somewhat larger in diameter than the maximum diameter of the ribbon accumulated on the ribbon spool so that the feed roller 61 engages the knurled surface of the feed roller 79 under the tension of spring 63, arm 66 being held clear of pin 62 as in Fig. 12.

The plate 28 for the left-hand feed unit (Figs. 1, 2, 3 and 5) is considerably larger than the plate 35 for the right-hand unit and extends rearwardly to form a support for a spool of carbon ribbon S. This spool is supported by a vertical shaft 31 mounted in the same general fashion as the shafts 29 and similarly provided with a brake 40 comprising the spring 33, disk 34, and washers 35 and 36 to prevent the spool S from unwinding too freely, and the spool S is constructed very similarly to the spools 30 except that the flanges are considerably larger in diameter. The threading of the carbon ribbon CR is indicated by dotted lines in Fig. 1 and it will be seen that it follows the same path as the ribbon R with respect to the left-hand unit but, with respect to the right-hand unit, the carbon ribbon is passed directly around the knurled feed roller 79, underneath the feed roller 61, and allowed to feed to one side of the machine, the ribbon being discarded after one use.

Provision is made for stopping the machine or otherwise controlling it or warning the operator that the carbon ribbon is exhausted. This means consists of a feeler arm 82 (Figs. 1, 2, and 5) which is pivoted on a stud 83 carried by the left-hand plate 28 and carrying a roller designed to ride on the coil of ribbon on the spool S and urged in a counterclockwise direction by a spring 84 (Fig. 5). The feeler lever 82 (Figs. 3 and 5) has an arm 82a formed with a downward extension 82b capable of engaging the operating arm 85 of a sensitive switch SC of the same type as the magnets RHFM, LHFM to operate said switch when the spool S becomes completely uncound. The switch SC is of the normally closed type.

When loading the machine with carbon or hectograph ribbons it is desirable that the arm 82 be locked in a disengaged position and for this purpose there is provided a catch 86 (Figs. 1 and 5) pivoted at 87 on the plate 28. The catch is urged in a counterclockwise direction by a spring 88 and is formed with a shoulder or notch

86a engaging a part of the arm 82 to the right of the pivot 83 to hold the arm 82 in disengaged position as in Fig. 5. The catch 86 has an upstanding lug 86b serving as a finger-piece for releasing the catch 86 when the new spool of carbon ribbon has been placed on the shaft 81.

The switch SC may be placed in the circuit for the clutch magnet CM (Fig. 11) machine so as to stop the operation of the machine as soon as the ribbon becomes exhausted. In the case of the application of the ribbon mechanism to a machine like a typewriter, the switch SC may be placed in series with the motor which drives the shafts 38, or the contacts may be placed in series with the circuit breaker contacts CB to prevent impulses being delivered to the magnets LHFM, RHFM.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. An inking ribbon feeding mechanism for office machines comprising a pair of ribbon feeding units, each unit including a driven shaft and a device for detecting the end of the ribbon; a continually operating main power shaft; a pair of normally disengaged clutches, one for each of said units, for coupling the driven shaft to said drive shafts; and means selectively controlled by said detecting devices for momentarily engaging one of said clutches.

2. An inking ribbon feeding mechanism for office machines comprising a main power shaft; a pair of ribbon feeding units, each including a ribbon spool, a drive shaft for said spool, a normally disengaged clutch for coupling the drive shaft to the main shaft; a magnet for actuating the clutch, and a device for detecting exhaustion of the ribbon spool, said detecting device including switch means; a source of electric pulses for said magnets, and means controlled by said switches for connecting first one of said magnets and then the other to said source of pulses.

3. An inking ribbon mechanism for office machines, comprising a power source, a pair of ribbon feeding spools, means for selectively coupling said spools to said power source including a pair of normally ineffective electro-mechanical coupling devices each having a magnet for rendering the coupling device momentarily effective, and contact means actuated by the ribbon for selecting said magnets.

4. In ribbon feeding mechanism for office machines, a main power source; and a pair of self contained ribbon feeding units, each comprising a ribbon spool, a drive shaft therefor, a normally disengaged clutch for coupling the drive shaft to the power source, a magnet for actuating the clutch, and switch means actuated by the ribbon for closing a circuit to the magnet when the spool for such unit is exhausted.

5. An inking ribbon mechanism comprising a pair of ribbon spools, a main power shaft, normally inactive means to couple said ribbon spools to said power shaft including a clutch for each spool and a magnet for engaging said clutch, means tending to pulse said magnets at periodic intervals to feed said ribbon intermittently, a relay for selecting the magnet to be pulsed, and contact means associated with said spools and operative to alternately energize and deenergize said relay according to which of the spools becomes exhausted of ribbon.

6. An inking ribbon mechanism comprising a pair of ribbon spools, a main power shaft, means to clutch said ribbon spools to said power shaft including a clutch for each spool and a magnet for engaging said clutch, means tending to pulse a selected one of said magnets at periodic intervals, a relay for selecting the magnet to be pulsed, and a pair of contact devices, one for each spool for first closing a circuit to said relay when one spool becomes empty and then opening the circuit to said relay when the other spool becomes empty.

7. An inking ribbon mechanism comprising a pair of ribbon spools, a main power shaft, means to clutch said ribbon spools to said power shaft including a clutch for each spool and a magnet for engaging said clutch, means tending to pulse said magnets at periodic intervals, a relay for selecting the magnet to be pulsed; and a series circuit for said relay including a pair of switches, one for each spool, one switch being closed when its associated spool becomes empty and the second switch being opened when the other spool becomes empty.

8. An inking ribbon mechanism comprising a pair of ribbon spools, a main power shaft, means to clutch said ribbon spools to said power shaft including a clutch for each spool and a magnet for engaging said clutch, means tending to pulse said magnets at periodic intervals, a relay selecting the magnet to be pulsed, means associated with said ribbon spools for detecting the exhaustion of the ribbon, and contact means in circuit with said relay and alternately closed and opened by the detecting means according to which of said spools is exhausted.

9. An inking ribbon mechanism comprising a pair of ribbon spools, a main power shaft, means to clutch said ribbon spools to said power shaft including a clutch for each spool and a magnet for operating said clutch, means tending to pulse said magnets at periodic intervals, a relay for selecting the magnet to be pulsed; a pair of ribbon exhaustion detecting members, one for each spool; and a pair of switches, each actuated by one of said members, in circuit with said relay, one of said switches being normally open and closed by its associated member to energize said relay and select the clutch magnet corresponding to the exhausted spool, the other of said switches being normally closed and opened by its associated member when the second spool is exhausted to thereby deenergize said relay and select the other of said clutch magnets.
